UNITED STATES PATENT OFFICE.

WILLIAM S. SEYMOUR, OF PHILADELPHIA, PENNSYLVANIA, ASSIGNOR TO PENNSYLVANIA TUBE COMPANY, OF PHILADELPHIA, PENNSYLVANIA, AND CAMDEN, NEW JERSEY, A CORPORATION OF NEW JERSEY.

UMBRELLA-TIP.

SPECIFICATION forming part of Letters Patent No. 693,745, dated February 18, 1902.

Application filed April 11, 1901. Serial No. 55,366. (No model.)

To all whom it may concern:

Be it known that I, WILLIAM S. SEYMOUR, a citizen of the United States, residing in Philadelphia, Pennsylvania, have invented 5 certain Improvements in Umbrella-Tips, of which the following is a specification.

The main object of my invention is to finish the tip of an umbrella or parasol and to prevent the metallic tube which forms the stick 10 splitting or fraying.

A further object of the invention is to provide an additional shoulder or bearing to take the thrust of the tip-piece.

In the accompanying drawings, Figure 1 is 15 a perspective view of a tip of an umbrella, illustrating my invention. Fig. 2 is a perspective view of the parts detached. Figs. 3, 4, 5, and 6 are sectional views showing the different stages in the manufacture of my invention. Fig. 7 is a side view. Fig. 8 is 20 a section on the line 8-8, Fig. 5, showing one form of tube; and Fig. 9 is a view similar to Fig. 8, showing another form of tube.

In the manufacture of umbrellas and 25 parasols, especially umbrellas, it is necessary that the tip or end of the umbrella-stick should be made sufficiently strong to withstand the rough usage to which it is subjected. Metallic tubes, which are now universally used to form 30 the stick of the umbrella, are generally made with butt-joints, the seam being closed by brazing. This form of tube is shown clearly in the sectional view Fig. 9. Another form of tube for which I have obtained a patent is 35 made by coiling a sheet of metal around a mandrel, forming a tube, one layer overlapping the other, as shown in the sectional view Fig. 8. The butt-joint tube is liable to split at the end by the constant striking of the tip 40 in the use of an umbrella as a cane, and in the other case the overlapping portion of the thin metal from which the tube is made may fray or become detached at the end from the same cause. The shoulder formed by the 45 end of the tube is not sufficient to resist this pressure. By my invention I not only prevent a butt-joint tube from splitting and a coiled tube from fraying by the use of a sleeve, but I also form a shoulder within the tube 50 which takes considerable of the thrust of the

tip-piece, so that I am enabled to prevent injury to the end of the tube and at the same time give a finish to the tip of the umbrella.

A is the tube, which may be either in the form of a butt-joint tube or a lapped or coiled 55 tube or, in some instances, may be in the form of a seamless tube.

B is the tip-piece, having a head b and a shank b'. This shank snugly fits within the tube. D is a tapered ferrule which fits over 60 the tip, as shown in the drawings.

In finishing a tip for an umbrella in accordance with my invention the shank b' of the tip-piece B is placed within the end of the tube, as illustrated in Fig. 3. Then the tube 65 is swaged by the ordinary swaging-machine, so as to contract the end a of the tube and force it tightly onto the shank b', as shown in Fig. 4. This swaging operation displaces the metal of the shank b', causing it to elongate, as illustrated in said figure, and the shank is made tapered, being smaller at the head than at the opposite end, so that after the swaging it is impossible for the shank to be removed. At this point the ordinary process of finishing an umbrella-tip stops, and it 75 will be seen that the only resistance against pressure is the shoulder formed by the end of the tube, and if the joint of a butt-joint tube is imperfect at this point it will readily split by 70 the constant blows against the tip, and in the case of a lapped tube the seam may open. I place on the tapered portion of the tip a ferrule D, as illustrated in Fig. 5. This ferrule extends only to the head of the tip-piece, so as 80 not to overlap the head, and is of sufficient length to extend beyond the end of the shank b'. The tip with the ferrule in position is then placed in a swaging-machine and swaged, so as to reduce the diameter of the ferrule and 85 again reduce the diameter of the tube, as well as elongate the shank of the tip-piece. By making the ferrule longer than the shank and by swaging the ferrule beyond the end of the shank I form a shoulder a' directly back of 90 the shank b' by reducing the diameter of the tube, as it is free to be contracted, owing to the fact that the shank is discontinued. By contracting the tube at this point I not only 95 form a shoulder to take the thrust of the tip- 100

piece B in addition to the end a^2 of the tube, but I also form an additional shoulder at a^3 by the ferrule D, which is swaged so that its outer surface will be even with the head b of the tip. Furthermore, by swaging the entire ferrule I force the ferrule to displace the metal of the tube, so that its outer surface will be even with the outer surface of the tube, consequently making an even finish to the tip without any shoulders or projections exposed, and I provide an additional shoulder within the tube at a' to take the thrust of the tip-piece, and I also provide an additional shoulder at the end of the tube a^2 , as the ferrule as well as the tube rest against the head of the tip-piece.

I claim as my invention—

1. The combination of a metallic tube forming the stick of an umbrella, a tip-piece having a head resting against the end of the tube, a shank within the tube, and a ferrule mounted on the tube, the ferrule and tip being secured to the tube by swaging whereby the metal of the shank is displaced and the tube and ferrule contracted, substantially as described.

2. The combination of a metallic tube forming an umbrella-stick, a tip-piece having a head and shank, the shank fitting within the tube, the tube being secured to the tip-piece by swaging, and a ferrule mounted on the tube back of the head of the tip-piece, substantially as described.

3. The combination of a metallic tube forming an umbrella-stick, a tip-piece having a head and shank, the head resting against the

end of the tube and the shank mounted within the tube, a sleeve mounted on the tube and extending beyond the end of the shank, the said parts being secured together by swaging so as to form a shoulder back of the end of the shank, said shoulder taking, with the end of the tube, the thrust of the tip-piece, substantially as described.

4. The combination in an umbrella-tube, of a metallic tubular stick, a tip-piece having a head and shank, the head resting against the end of the tube and the shank within the tube, a ferrule mounted on the tube and extending from the end of the tube to a point beyond the shank, the said parts being secured together by swaging so as to displace the metal of the shank and to contract the tube and ferrule, whereby a shoulder is formed back of the shank and the outer surface of the ferrule is on a line with the tip and the outer surface of the tube, substantially as described.

5. The combination in an umbrella-tip, of a butt-joint metallic tube, a tip-piece having a head and shank, the said shank being mounted within the tube, a ferrule mounted on the tube, a shoulder within the tube back of the shank of the tip-piece, said shoulder taking, with the end of the tube, the thrust of the tip-piece, substantially as described.

In testimony whereof I have signed my name to this specification in the presence of two subscribing witnesses.

WILLIAM S. SEYMOUR.
